UNITED STATES PATENT OFFICE

HERBERT THOMAS COX, OF LOS ANGELES, CALIFORNIA.

CARD GAME.

Application filed April 2, 1925. Serial No. 20,238.

To all whom it may concern:

Be it known that I, HERBERT THOMAS Cox, a citizen of the United States, and a resident of Los Angeles, in the county of Los Angeles and State of California, have invented certain new and useful Improvements in Card Games, of which the following is a specification.

This invention relates to card games and 10 has for its object the provision of a plurality of main suits of cards with a plurality of honor suits cooperating with the main suits to form combinations which will eventually result in a predetermined number 15 of cards designating the winner.

This invention will be best understood from a consideration of the following detailed description, in view of the accompanying drawing forming a part of the 20 specification; nevertheless it is to be understood that the invention is not confined to the disclosure, being susceptible of such changes and modifications which shall define no material departure from the salient 25 features of the invention as expressed in the appended claims.

In the drawings,

Figure 1 shows a plan view of a plurality of one series of honor suits designated as 30 "green backs".

Figure 2 is a plan view of a series of another honor suit designating industries.

Figure 3 shows a plan view of a series of honor cards distinguished by fruits.

35 Figure 4 discloses a series of an honor suit designated as "grain".

Figure 5 shows an individual suit card designated as the bank.

Figure 6 shows a series of suit cards and 40 a captain card designated by automobiles.

Figure 7 shows another series of suit cards designated by ships, with a captain card.

45 Figure 8 shows another series of suit cards designated by aeroplanes, with its captain card.

Figure 9 shows a series of directional cards employed in the game.

50 Referring more particularly to the drawings, a group series of the cards are shown by Figures 1 to 4 inclusive which are described as honor cards, with each honor suit containing four cards. In Figure 1 a green back card designated by the numeral

1 is one of a series of honor cards of which 55 there are four in number and which are numerically designated as 1 to 4 inclusive.

In Figure 2 is shown another group of honor cards numbered 1 to 4 and representing the industries such as manufacturing, 60 oil, fishing and mining and respectively designated by the numerals 2, 3, 4 and 5. These cards have a single illustration printed in blue.

In Figure 3 is shown four other honor 65 cards printed in red and generally representing a broad class of fruits with the sub-combinations of the fruits disclosed by an illustration of one particular fruit on each card such as strawberries, apples, cherries 70 and grapes, the cards being respectively designated by the numerals 6, 7, 8 and 9. The third class of honor cards of which there are four in number are printed in yellow and illustrate sub-classes of the general 75 classes of grains and as such the card designated by the numeral 10 represents wheat, the other three cards designated respectively by the numerals 11, 12 and 13 represent barley, oats and corn. 80

The suit cards shown in Figures 5 to 8 inclusive are printed in black and one of the suit cards 14 represents a bank. It will be noted that this card is not numbered 85 since only one card is employed in the game.

In Figure 6 a suit card is shown having an illustration of an automobile and there are five of these cards numbered from 1 to 5 inclusive with a set of four of each numbered card. In other words, there will be 90 20 automobile cards and which are designated by the numeral 15. For each set of automobile cards there is a captain card designated by the numeral 16 having an illustration similar to the card 15 but having 95 the indicia "Captain" printed between the pair of automobiles and with a letter C as shown at 17 replacing the numeral shown at 18 in the card 15.

The cards shown in Figures 7 and 8, 100 together with the card shown in Figure 6, represent modes of travel and as such belong to the broad class under such title with the individual modes represented by each series of cards. In Figure 7, suit card designated 105 by the numeral 19, has opposed illustrations on its face showing a method of travel on water and represented by a sailing vessel.

These cards are likewise numbered from 1 to 5 inclusive. A captain card 20 distinguished by the indicia "Captain" is also employed in this group. The third group 5 of cards in the mode of travelling is illustrated by a pair of aeroplanes in opposed relation and these cards 21 are also numbered 1 to 5. A captain card 22 is also provided which may be substituted for any one of this 10 group during the game.

In Figure 9 is disclosed what I term a directional card indicated by the numeral 23. Two of these cards respectively designated by the numerals 24 and 25, are provided with indicia such as "Retailer" and "Wholesaler." Upon the backs of the retailer and wholesaler cards of which there is one apiece is printed the word "Director" as shown in card 23. The cards 23, of 15 which there are six in number, have their faces blank and play no important part in the playing of the game other than aiding in properly distributing in a secret manner the retailer and wholesaler cards. It will 20 thus be seen that there are eight directional cards as will be presently described. The retailer and wholesaler cards when drawn will indicate the players who aid in initiating the game.

30 Rules of play:

The game is played always as individuals and not as partners, and may be played by two, three or four players. Four players 35 are the preferable number and the following procedure applies for such a number of players.

40 *The shuffle.*—The eighty cards are all placed face down in a pile loosely, and are stirred about with the hands to thoroughly mix them. Then they are placed in one pile in the center of the table. Another method suggested is that each player take approximately one-fourth of the cards and shuffle his portion and then the four shuffled portions can be placed in one pile in the center 45 of the table.

50 *Dealing the cards.*—The cards having been thoroughly shuffled and placed as instructed, the directors cards, eight in number, are shuffled and dealt around one at a time face up to all of the players, thus supplying two to each player. The deal is made by any one of the players.

55 The player obtaining the wholesaler card now takes the pack from the table and beginning with himself deals the cards around face down to his left into four piles, one in front of each player. These four piles 60 are called supply bases.

The player having the retailer card takes the supply base in front of him, which is known as supply base No. 1, and deals to his right one card at a time until each player 65 has eight cards. When base No. 1 is ex-

hausted, he picks up the first base pile to his right and continues until the eight are dealt to each player.

The supply bases are numbered from one to four, beginning with the retailer's as No. 1 70 and passing around to his right, 2—3—4. The same player may draw both wholesaler and retailer cards; in that case he acts as each.

Object of the game.—The cards with the exception of the greenbacks have no value 75 individually but only as they appear in scoring combinations in the player's hand. The winner of the game is the player who first, by means of a series of draws and discards, 80 obtains a complete hand, containing as many counting combinations as possible.

A completed hand.—A complete hand is made up of combinations of three or four, and one pair, eight cards in all except for 85 each greenback or set of four of a kind, the hand will contain one more card than eight. Three or more suit cards of a kind count as a combination; two may be used as a pair but do not count. Two or more honor cards of a kind count, but one each of two kinds can not be counted as a pair. Each greenback counts individually only and not in combination. As soon as a combination of 90 three of a kind is obtained it must be played out in front, i. e. laid face up in front of the rack.

Playing.—Each player takes his hand 95 which is the eight cards dealt by the retailer, and places them on the back of his rack facing him, arranging them in groups 100 according to the kind to aid in playing. The retailer begins the game by drawing the top card from the supply base, which 105 was partially used in the deal, and discarding either one of his other cards or the one just drawn. When he discards he plays the card face up in the center of the table, and calls it out by name, so that the other 110 players may see and hear.

If no player cares to take the discarded card, the next player to his right or Number 2, plays in the same manner by drawing the top card from the same supply base, and discarding one to the center of the table 115 in the same manner as the retailer had done. Then the player to the right of the second player or Number 3 plays in the same manner, and so on, each player retaining the cards that he thinks will be most valuable in completing his hand, until one 120 player completes his hand and wins.

When a player has completed his hand he announces it by calling out "I sell out", and then all players place their cards on the front of their rack in a row face up, and the scores are counted.

The order of play is always to the right 125 hand or counter-clockwise from the retailer who is the first player, and the cards 130

are drawn from the top of the supply base to the right or counter-clockwise from the last one used until some player completes a hand or all of the cards have been used.

If no one completes a hand before all the cards are drawn each player then places his cards out and the score of each player is counted.

- 10 The procedure for every player in his regular turn of play is to draw one card from the supply base and discard one card, but if he has taken a discarded card when it was his turn to play, then he does not 15 draw from the supply base but must discard one to finish his play. No player can draw until the preceding player's discard has been placed face up on the table and has his hand removed from it; also no 20 player can discard until after he has drawn a card or bought the previously discarded card.

If any player should have a pair of cards similar to a card discarded by a player, he 25 can take it by saying, "I buy". He then plays out his combination in front of his rack and discards one card from his rack. The play then passes to the next player to his right, and if any players intervene 30 between him and the one who discarded the captured card they lose their turn. After a card is bought a player must discard but does not draw a card from the supply base until his next turn.

35 *The special cards.*—In the suit cards are the captains, one in each suit, which may be used as any other number in that suit to complete a combination, if two cards of like number are held, or the captain can be used to make a pair with one other card and in so doing a player can sell out. A captain can not be bought unless two like cards of the same suit and same number are held with which to match it to complete a combination of three, or to match with a single card of that suit when it completes a pair so that a player may sell out. Examples:—If a player has two 4's of automobiles, he can buy the captain of 40 automobiles to make three 4's, or if he should have one 4 of automobiles and need only to complete that pair to sell out he may buy the captain to complete the pair of 4's.

45 The bank card doubles the score of the player drawing it, when the score is counted, and besides it may be used for any other card in the deck, in order to complete a hand, that is, if a player's hand is 50 complete except for one card he can employ the banker's card for that card which is needed and sell out. The player's score is counted using the banker's card in its substituted place and then his total score 55 doubled.

The honor cards.—In the honor cards of fruits, grains or industries, two of a suit count in the score when used as a pair to complete a hand, but three of a suit must be used to complete a combination, the same 70 as the regular suits, that is, two grains will count when they complete a hand as a pair, or three grains used as a combination, there being only four grains in the pack. No two of the cards of course will have the same 75 picture or number. An honor card can not be bought when discarded unless the player buying it holds two cards of that suit on his rack.

The greenbacks upon being drawn are 80 immediately placed out in front of the rack and another card drawn from the bottom of the supply base No. 4 to take its place, and then one card is discarded. Each greenback counts 3 except if a player draws the 85 greenback with the number corresponding with the number of his supply base it counts double or six points.

The method of counting the suit cards which applies to all hands, is as follows:— 90

	Points.
Three of a kind (of 1, 2, 3, or 4) of the same suit	3
Three 5's of the same suit	5
Four of a kind (of 1, 2, 3, or 4) of the same suit	95
Four 5's of the same suit	10
Honor cards:	
Two of a suit of fruit, grains, or industries	3 100
Three of a suit of fruit, grains or industries	5
Four of a suit of fruit, grains or industries	10 105
Greenbacks each counts	3
Greenback of player's own number supply base	6
Bank card doubles the player's score.	

The game.—The cards are played around 110 four times or in other words four completed hands are played and then the scores earned by each player are added and the player having the highest score is the winner of the game.

Drawing a fourth card.—If a player has three cards forming a combination on the front of his rack exposed and should draw a fourth card of that suit he may lay it out also with the other three and draw one card from the bottom of supply base No. 4 to take its place and then discard one card as is done when a greenback is drawn. The fourth card materially increases the value of the combination. The fourth card can 120 not be taken from the discard but must be drawn by the player using it.

Penalty.—If the hand ends and a player does not have a clear hand 5 points are subtracted from his score; if he has no score he 130

is given a minus 5 score. A clear hand is understood to contain only cards of one suit as ships for example but devoid of aeroplanes or automobiles. The penalty does 5 not relate to any of the honor cards.

The bank card can not be matched with one suit card to make a pair with which to buy a discarded captain. Also the bank card can not be included in the same 10 combination of three to complete a hand.

If the bank card is drawn early in the game it is advisable not to use it to complete a combination or pair, but to reserve it to be employed as the last card needed to 15 complete the hand, since it may be substituted for any other card in the deck except a captain of a suit.

Choice of suits.—Each player should immediately decide after the first card is 20 drawn which suit is to be saved and begin to discard other suits, for the play may end before his hand can be cleared, causing a penalty on the player. Each player secretly decides which suit he is going to save and 25 does not announce it.

Rules for two or three players.—The only difference from the method followed by four players is in the starting of the game.

If three are to play two blanks are 30 removed from the directors' cards, using only six when they are dealt around.

If two are to play, four blanks are removed from the directors' cards, and four are dealt out to start the game.

35 In each case whether two or three play, the cards are dealt by the wholesaler into four piles of twenty each; the retailer being number one and the other piles numbered to the right, two, three, and four, regardless 40 of the positions of the players at the table. Each player using the number of the supply base in front of him, and the game is then carried on according to the rules for four players. When two are playing it is preferable to sit opposite each other at the 45 table, thus one would be number one and the other number three with piles numbers two and four one to either side of the table.

I claim:

50 1. A card game consisting of a plurality of suit cards, a plurality of honor cards, and a plurality of directional cards, the last mentioned cards indicating the players who initiate the game.

55 2. A card game consisting of a plurality of suit cards having indicia thereon illustrating modes of conveyance, a plurality of honor cards having indicia thereon designating certain industries, grains and fruits, 60 and directional cards for indicating the players who initiate the game.

65 3. A card game consisting of a plurality of suit cards having indicia thereon illustrating modes of conveyance, a plurality of honor cards having indicia thereon design-

nating certain industries, grains and fruits, and directional cards for indicating the players who initiate the game, the suit cards including a specially designated card having a greater value in a play than the other 70 suit cards, the honor cards including a series of cards having a greater value in a play than the other honor cards.

4. A card game consisting of a plurality of suit cards having indicia thereon illustrating modes of conveyance, a plurality of honor cards having indicia thereon designating certain industries, grains and fruits, and directional cards for indicating the players who initiate the game, the suit cards including a specially designated card having a greater value in a play than the other 75 suit cards, the honor cards including a series of cards having a greater value in a play than the other honor cards, the suit cards also including a card for each series which may be substituted for any one of the suit cards of a predetermined series.

5. A card game consisting of a plurality of suit cards having indicia thereon illustrating modes of conveyance, a plurality of honor cards having indicia thereon designating certain industries, grains and fruits, and directional cards for indicating the players who initiate the game including a 80 card for each series which may be substituted for any one of the suit cards of a predetermined series.

6. A card game consisting of a plurality of suit cards having indicia thereon illustrating modes of conveyance, a plurality of honor cards having indicia thereon designating certain industries, grains and fruits, and directional cards for indicating the players who initiate the game, two or more 85 cards of the honor series of like designation having a predetermined value, while three or more cards of the suit series having a predetermined value in the final count of the game.

7. A card game consisting of a plurality of suit cards, a plurality of honor cards, and a plurality of directional cards, the last mentioned cards indicating the players who initiate the game, the suit cards including a 90 specially designated card having a greater value in a play than the other suit cards, the honor cards including a series of cards having a greater value in a play than the other honor cards.

8. A card game consisting of a plurality of suit cards, a plurality of honor cards, and a plurality of directional cards, the last mentioned cards indicating the players who initiate the game, the suit cards including a specially designated card having a greater 95 value in a play than the other suit cards, the honor cards including a series of cards having a greater value in a play than the other honor cards, the suit cards also in-

cluding a card for each series which may be substituted for any one of the suit cards of a predetermined series.

9. A card game consisting of a plurality of suit cards, a plurality of honor cards, and a plurality of directional cards, the last mentioned cards indicating the players who initiate the game, the suit cards including a specially designated card having a greater value in a play than the other suit cards, the honor cards including a series of cards having a greater value in a play than the other honor cards, the suit cards also including a card for each series which may be substituted for any one of the suit cards of a predetermined series and directional cards for indicating the players who initiate the game.

10. A game of cards consisting of a plurality of honor cards arranged in predeter-

mined series, each series comprising a definite number of cards relating to a class of objects, and each card of the class being distinguished from the other cards of the class by an illustration representing an individual of the class, the cards representing values in groups of two or more, one series of the honor cards having a greater value than the cards of the other series, and suit cards composed of a plurality of series of cards illustrating various subcombinations of a general class of objects, and a card which when employed being effective to increase the final count, one of the suit cards of each series having indicia distinguishing the same as a substitute for any of the suit cards of a series, the suit cards being prescribed values in groups of three or more of each series.

HERBERT THOMAS COX.
